(57) **CLAIM**

The ornamental design for a motorcycle wheel front face, as shown and described.

DESCRIPTION

FIG. 1 is a first perspective view of my new motorcycle wheel front face, according to the present invention; and, FIG. 2 is a front elevational view thereof.

The broken lines shown in FIG. 1 and FIG. 2 of the drawings are for illustrative purposes only, and the subject matter depicted thereby constitutes no part of the claimed design.

1 Claim, 1 Drawing Sheet

FIG. 1.

FIG. 2.
